(57) **CLAIM**

The ornamental design for a pushing mechanism, as shown and described.

DESCRIPTION

FIG. 1 is a perspective view of a pushing mechanism according to an embodiment of the present design with a spring and various fastening components shown in broken lines.

FIG. 2 is a front elevation view of the pushing mechanism of FIG. 1.

FIG. 3 is a rear elevation view of the pushing mechanism of FIG. 1.

FIG. 4 is a right side elevation view of the pushing mechanism of FIG. 1.

FIG. 5 is a left side elevation view of the pushing mechanism of FIG. 1.

FIG. 6 is a top plan view of the pushing mechanism of FIG. 1; and,

FIG. 7 is a bottom plan view of the pushing mechanism of FIG. 1.

The broken lines shown in FIGS. 1 through 7 illustrate portions of the pushing mechanism that form no part of the claimed design.
